RECORD CHANGING PHONOGRAPH

Johan Samuel Zandelin, Stockholm, Sweden, assignor to Industriaktiebolaget Luxor, Motala, Sweden, a corporation of Sweden

Application June 5, 1947, Serial No. 752,739
In Sweden December 8, 1945

Section 1, Public Law 690, August 8, 1946
Patent expires December 8, 1965

2 Claims. (Cl. 274—10)

1

The present invention relates to phonographs provided with a record changing mechanism of the type in which a stationary post extends upwards from the centre of the turntable and has an offset upper portion so as to form at the base of said offset portion a shoulder for supporting a pile of records of which the lowermost one may be moved laterally into concentric relation with the post by a record displacing member and thereby released so as to fall on to the turntable.

In the operation of the known mechanisms of this kind disturbing noise is produced as a consequence thereof that when the record feeding member has moved the lowermost record into concentric relation with the stationary post this record is pushed downwards under the weight of the remainder of the pile which imparts a high initial velocity to the same so that it strikes rather violently against the turntable.

It is an object of the present invention to eliminate this drawback.

Other objects of the invention will become apparent from the following description of a preferred embodiment thereof, reference being had to the accompanying drawing in which Figs. 1 to 5 are side elevations partly in section of the mechanism showing the same in different positions during the record changing cycle.

In the drawing 1 denotes a central stationary post extending upwards from the centre of the turntable (not shown) and having an offset upper portion 2. At the upper end of the post 1 a shoulder 3 is formed which is adapted to support a pile of records 4, the distance between this shoulder and the lower end 5 of the offset portion 2 being sufficient to permit the lowermost record 6 of the pile to be moved laterally into concentric relation with the post 1. The post 1 has a longitudinal slot in which a rod-shaped record displacing or feeding member 7 is rotatably mounted on a transverse pin 8 which extends through an elongated aperture 9 in the displacing member 7 so that this member may also be moved in a vertical direction in the post 1. At its upper end the rod-shaped member 7 has a projection 12 at the base of which a supporting shoulder 11 is formed.

The lower end of the record feeding member 7 projects downwards from lower end of the post 1 and is formed with a ball-shaped end piece 10 adapted to engage a peripheral cam groove 13 provided in a rotatably mounted roll 14. The cam groove 13 follows a particular curve in axial direction and the depth of the same varies in peripheral direction. The roll 14 is adapted to

be rotated once during each record changing operation in the direction of the arrow 15 by a suitable mechanism. This rotation of the roll 14 causes the record feeding member 7 engaging the cam groove 13 to be moved as described hereinafter.

Fig. 1 shows the starting position when a change of records is to take place. In this position the pile 4 rests on the shoulder 3 of the post 1. When the roll 14 is caused to rotate in the direction of the arrow 15 the record feeding member 7 is first moved upwards so that the pile 4 after having been engaged by the shoulder 11 of the member 7 is raised from the shoulder 3 of the post 1, as shown in Fig. 2. Then the record feeding member 7 is swung clockwise about the pin 8 moving the lowermost record 6 to the right into concentric relation with the central post 1, as illustrated in Fig. 3. Next the record feeding member 7 is lowered so that the pile 4 is gently placed upon the shoulder 3 of the post 1 while the record 6 is further lowered and separated somewhat from the pile 4 (Fig. 4). The record 6 is now free from the weight of the pile and is supported by the shoulder 11 of the record feeding member 7. Now this member 7 is swung counter-clockwise into concentric relation with the central post 1 thereby causing the shoulder 11 to release the record 6 so that this record falls gently and without disturbing noise on to the turntable. The upward movement of the record feeding member 7 from the position shown in Fig. 5 to that shown in Fig. 1 may be effected immediately after said member has reached the first-mentioned position or, if desired, at the beginning of a new record changing operation in which latter case the position shown in Fig. 5 would be the starting position. As will be seen from the drawing the only frictional wear on the records will be that which occurs when the lowermost record is moved laterally from the position shown in Fig. 2 to that shown in Fig. 3 and slides with its upper surface against the lower surface of record above the same, and when the shoulder 11 of the record feeding member 7 is retracted from its supporting position in Fig. 4. In the latter case, however, the record 6 has been separated from the remainder of the pile so that the friction will be rather small.

According to a modification the record feeding member 7 may be only rotatably connected to the central post 1 in a position corresponding to that shown in Fig. 1, so that when the record feeding member is swung clockwise the lowermost record 6 is displaced laterally into concentric

relation with the post 1 and caused to fall on to the shoulder 11 of the record feeding member 7 which shoulder is located below the shoulder 3 of the post 1. When the record feeding member is swung back the shoulder 11 releases the said record and allows the remainder of the pile 4 to fall on to the shoulder 3 of the post 1.

It is obvious that other variations may be made in the embodiment above described without departing from the scope of the invention as defined by the following claims.

What I claim is:

1. In a record changing phonograph, a stationary post having an offset upper portion to provide a shoulder for temporarily supporting a pile of records of which the lowermost record may be displaced laterally into concentric relation with the post, a record displacing member swingably mounted on a transverse pivot in said stationary post and also movable in longitudinal direction, said record displacing member being provided at its upper end with a projection adapted normally to engage the central hole of the lowermost record of the pile and with a shoulder arranged at the base of said projection substantially at a level with the shoulder of the post, when the displacing member is in its upper position, for temporarily supporting the pile of records when the displacing member is swung to a position in which said shoulder is outside the periphery of said stationary post, and a driving mechanism for said displacing member, said driving mechanism being adapted first to swing the record displacing member in a direction for moving the lowermost record of the pile into concentric relation with the post, then to lower the record displacing member so as to separate the lowermost record from the remainder of the pile and place the latter upon the shoulder of the post, then to swing the record displacing member back so as to release the record supported by the same and allow said record to descend along the post, and finally to raise the record displacing member so as to cause the upper projection thereof to engage the central hole of the next record of the pile.

2. In a record changing mechanism, a stationary post having an offset upper portion to provide a shoulder for temporarily supporting a pile of records of which the lowermost record may be displaced laterally into concentric relation with said post, a record displacing member swingably mounted on a transverse pivot in said post and also in longitudinal direction with respect to the same, said record displacing member being provided at its upper end with a projection and with a shoulder at the base of said projection for temporarily supporting the pile of records, when the displacing member is swung to a position in which said shoulder is outside the periphery of said stationary post, and a driving mechanism for said record displacing member, said driving mechanism being adapted first to move the record displacing member upwards so as to cause the shoulder thereon to engage the pile of records and raise the same from the shoulder of the post, then to swing said record displacing member in a direction for moving the lowermost record of the pile into concentric relation with the post, then to lower the record displacing member so as to separate the lowermost record from the remainder of the pile and place the latter upon the shoulder of the post, and finally to swing the record displacing member back so as to release the record supported by the same and allow said record to descend along said post.

JOHAN SAMUEL ZANDELIN.
